UNITED STATES PATENT OFFICE.

JOHN STERN, OF DETROIT, MICHIGAN.

SHEET-METAL VESSEL.

SPECIFICATION forming part of Letters Patent No. 415,984, dated November 26, 1889.

Application filed February 26, 1889. Serial No. 301,216. (No model.)

To all whom it may concern:

Be it known that I, JOHN STERN, a citizen of the United States, residing at Detroit, in the county of Wayne and State of Michigan, have invented certain new and useful Improvements in Sheet-Metal Vessels, of which the following is a specification, reference being had therein to the accompanying drawings.

10 This invention relates to new and useful improvements in sheet-metal vessels; and the invention consists in the peculiar combinations and construction of parts, all as more fully hereinafter described, and shown in the 15 accompanying drawings, in which—

Figure 1 is a perspective view of an ordinary sheet-metal pail or can to which my metallic band is applied. Fig. 2 is a vertical central section thereof. Fig. 3 is a horizontal section on line X X in Fig. 2.

A is a sheet-metal pail.

B is a groove pressed in and around the wall of the same.

C is a metallic band, preferably made of 25 steel, and secured in the groove B, so as to fit firmly into the can for the purpose of stiffening and strengthening the same, to prevent the elongating of the vessel or can when it is filled with heavy material—such 30 as paint, white lead, &c.—and lifted by its bail.

It is a common difficulty with the ordinary paint-cans and like metallic vessels provided with the common wire bail that when 35 filled and lifted up by the bail the can contracts or flattens on the top unless it is especially strengthened. This contraction is caused by the weight of the material, which bends the bail and causes the two opposite 40 sides to draw together and so elongates the vessel. This contraction necessarily causes the overflow of the material when the can is filled, and much material is wasted in this manner by the use of the ordinary tin 45 pail when carried by its bail and filled with a heavy mixture—such as white lead or paint.

In the putting up of paint in the ordinary tin cans, where a vessel is filled before the 50 cover is put on, it causes a great deal of

trouble and loss of time to try to put the cover, which forms a regular circle, on top of the can when the latter had been drawn out of shape and made irregular by handling. My invention is designed to entirely 55 overcome all these difficulties, as the steel band prevents the tin can from assuming an irregular shape if carried by its bail, or if it should become slightly irregular the steel band will always draw it back to its regular 60 form, so as to exactly fit the cover, and allowing it to be seamed to the can and without any trouble whatever. By pressing the groove into the wall of the vessel the band will become flush with the outside of the 65 wall of the vessel, and is thereby held in place, and it also presents an even surface on the outside, so that the labels may be put on smoothly. My metallic band also forms extra facility as a bail-fastener, as by means 70 of a slight corrugation D in the band on opposite sides of the vessel suitable bail-ears are formed, to which the bail may be secured by placing a hole in such ears and hooking the bails therein, or in any other suitable 75 manner.

For the purpose of my invention it is generally sufficient to place one band around the vessel at or near the place where the bail is applied; but, if desired or necessary 80 to effect the purpose of my invention, more bands may be secured in the same manner. The ends of the bands are preferably secured by a rivet E through the wall of the can, preferably at the seam, where there is 85 extra thickness to hold the rivet, and the rivet-head may be covered on the inside with a little solder, if desired or necessary, to prevent leakage.

What I claim as my invention, and desire 90 to secure by Letters Patent, is—

1. A sheet-metal vessel or can provided with an annular groove near the top thereof and a steel band secured in said groove by means of a rivet passing through the 95 ends of the said band and the body of the can at the seams thereof, substantially as described.

2. As a new article of manufacture, a sheet-metal pail provided with a continuous steel 100

metal band secured in an annular groove in
the body of the vessel by a rivet through the
ends of the band, and having corrugations
formed in said band on opposite sides to
5 form ears to which the wire bail is attached,
substantially as described.

In testimony whereof I affix my signature,

in presence of two witnesses, this 4th day of
January, 1889.

JOHN STERN.
